United States Patent Office

Des. 179,495
Patented Jan. 1, 1957

179,495

SPEED REDUCER OR SIMILAR ARTICLE

Martin T. Schumb, Milton, Mass., assignor to The Murray
Company of Texas, Inc., Dallas, Tex., a corporation
of Delaware

Application May 27, 1955, Serial No. 36,268

Term of patent 14 years

(Cl. D55—1)

Fig. 1

Fig. 2

Fig. 1 is a perspective view showing the back and left-hand side of the speed reducer embodying my new design, and

Fig. 2 is a perspective view showing the front and right-hand side of the speed reducer.

I claim:

The ornamental design for a speed reducer or similar article, substantially as shown.
